UNITED STATES PATENT OFFICE.

ALFRED MARTIN, OF SOUTH BEND, INDIANA.

DESIGN FOR A CURTAIN-POLE AND SHADE-ROLLER SUPPORT.

47,004.

Specification for Design.

Patented Feb. 23, 1915.

Application filed November 12, 1914. Serial No. 871,792. Term of patent 7 years.

To all whom it may concern:

Be it known that I, ALFRED MARTIN, a citizen of the United States, residing at South Bend, in the county of St. Joseph and State of Indiana, have invented a new, original, and ornamental Design for Curtain-Pole and Shade-Roller Supports, of which the following is a specification, reference being had to the accompanying drawing, in which a perspective view of the device is shown.

I claim:

The ornamental design for a curtain pole and shade roller support as shown.

In testimony whereof I affix my signature, in the presence of two witnesses.

ALFRED MARTIN.

Witnesses:

G. K. SIMMONS,
CHAS. BYER.
